CIRCUIT BREAKER

Leonard J. Linde, Drexel Hill, and Joseph W. Seaman, Upper Darby, Pa., assignors to General Electric Company, a corporation of New York

Application September 22, 1939, Serial No. 296,084

6 Claims. (Cl. 200—116)

Our invention relates to circuit breakers, more particularly to manually-operated circuit breakers having current responsive means for opening them on overload, and has for its object a simple and reliable device of this character.

In accordance with our invention, we provide an operating arm which is normally latched in a predetermined relation with a pivoted contact operating member or switch member but unlatched in response to a predetermined maximum current to effect opening of the circuit breaker.

For a more complete understanding of our invention, reference should be had to the accompanying drawing in which Fig. 1 is a fragmentary perspective view of a circuit breaker embodying our invention and showing the switch in the closed circuit position; Fig. 2 is a view similar to Fig. 1, but showing the switch in the manually opened position; Fig. 3 is a similar view showing the switch in the automatic open position; while Fig. 4 is a fragmentary view showing a modified form of our invention.

Referring to the drawing in the form shown the circuit breaker comprises a contact arm 10 preferably made of electrically insulating material having a fixed pivot 11 and carrying a movable contact 12 which cooperates with a stationary contact 13. This contact arm is actuated by means of a toggle comprising two pairs of links 14 and 15 connected together by a movable pivot 16. The other ends of the links 14 are connected by a pivot 17 to the contact arm 10 while the other ends of the links 15 are connected to stationary pivots 18 and 18a having a common axis. This pivot 18 is mounted in any suitable manner on supporting plates which, for purposes of clarity, have not been shown. For example, parallel spaced supporting plates may be arranged between the links 15 and handle 26 for supporting the fixed pivot 18.

For purposes of operation, two parallel operating arms 19 and 20 are provided having their upper ends pivoted on the pivot 18 and their lower ends joined by a cross bar 21. These two arms are each mechanically connected to the adjacent switch member or link 15 so as to normally move with and actuate the links 15. This connection comprises for the arm 19 a latch arm 22 pivoted on a pivot 23 carried by the links 15 intermediate their ends and having its other end normally in abutting engagement with a lateral projection 24 secured to the arm 19. A similar connection, not shown in detail, is provided for the other arm 20. These connections, when the arm 22 engages the projection 24, prevent rela-

tive angular movement between the arm 19 and the corresponding switch member or link 15 toward each other, while relative angular movement in the opposite direction is prevented by a transverse projection 25 on the upper end of the arm 19 extending over the link 15.

A handle arm 26 is provided having its lower end pivoted on the pivot 18. This handle is connected by the helical overcenter tension spring 27 with the cross bar 21. Consequently, with the parts in the relative position shown in Fig. 1, movement of the handle toward the left-hand moves the overcenter spring to the left-hand side of the pivot 18 whereupon the arms 19 and 20 and the switch members or links 15, secured to them, are snapped in a clockwise direction about the pivot 18 to the position shown in Fig. 2. This breaks the toggle downward and moves the switch arm 10 to its open circuit position.

Current responsive means are provided for moving the latch arm 22 out of engagement with the projection 24 to thereby open the switch independently of the handle 26. This means comprises suitable current responsive means shown as a loop shaped bimetallic thermostat 28 having a projection 29 on its upper free end which normally engages and holds up a trip lever 30 preferably made of electrically insulating material and having a fixed pivot 31. This lever is biased by a spring 32 in a counterclockwise direction, as seen in the drawing, about the pivot 31. The opposite end of the lever 30 is provided with a pin and slot connection 33 and 34 with an arm 35, the other end of which is mounted on the movable pivot 23.

Normally with the latch lever 30 held by the thermostat as seen in Fig. 1, the pivot 33 is in such position that its axis is coincident with the axis of the fixed pivot 18. Consequently, when the switch is operated manually, the arm 35 is free to rotate about the pivot 33.

As indicated diagrammatically by the conductors 36, 37 and 38, the bimetallic thermostat is connected electrically in circuit with the contacts 12 and 13. Upon the occurrence of a predetermined maximum current in the switch, the thermostat is heated to such an extent by the current passing through it that its upper end moves toward the left hand far enough to release the latch lever 30. The lever thereupon is rotated in a counterclockwise direction by the spring 32 whereby the arm 35 is moved about the pivot 23 in a clockwise direction to disengage the latch arm 22 from the projection 24. Thereupon the toggle is broken downward by a tension spring

39 connecting the bar 21 with the floating pivot 16 of the toggle. This opens the switch, the parts being then in the relative positions indicated in Fig. 3.

To reclose the switch, the handle is moved from the position shown in Fig. 3 toward the left hand, i. e., toward the open circuit position. During this movement, a projection 48 on the handle engages the right-hand end of the latch lever 30, thereby moving it back to its latched 10 position where it is secured by the thermostat, assuming of course that the thermostat has cooled to such an extent that its upper end has returned to a latching position. This also moves the arm 35 downward about the pivot 23, this movement being initially independent of the latch arm 22 which then rests, as shown in the drawing, on the projection 24. As shown, the latch arm 22 has a projection 41 bent laterally over the arm 35 so that when the arm 35 is raised, the 15 arm 22 is carried with it to its unlatched position. The arm 35 is free to move, however, against the force of a biasing spring 42 in a counterclockwise direction independently of the arm 22. When the handle 26 has moved far enough for the spring 27 to pass to the left-hand side of the stationary pivot 18, the arms 19 and 20 are snapped to their open circuit positions, the spring 39 being stretched since it is weaker than the spring 27. The latch arm 22 then is 20 moved downward behind the projection 24 by its biasing spring 42. The parts now are in the 25 position shown in Fig. 2 and the switch can be closed as previously described by moving the handle toward the right hand.

It will be understood that for simplicity and clarity in the description, a single one only has been referred to of certain of the parts which are provided in pairs. For example, the arm 20 is arranged in the same manner as the arm 19 with a projection, a latch arm, and an arm connected to the latch lever 30 corresponding to the parts 24, 22 and 35.

While the pivot pin 33 has been disclosed as having an axis coincident with the axis of the pivots 18 and 18a, it will be understood that substantial coincidence only is required in view of the fact that the pivot pin 33 may be displaced, for example, in a direction substantially at right angles to the latch lever 30. In such event, the slot 34 of course will have a curvature corresponding to the radius of movement of the end of the arm 35 about the axis of the pins 18 and 18a. This is indicated in Fig. 4 showing a pivot pin 43 and an arm 45 which correspond respectively with the pivot pin 33 and the arm 35 of Fig. 1. In Fig. 4 the pivoted pin 43 is displaced downward with respect to the axis of the pivot 18. Due to the displacement of the pin 43 slot 44 corresponding to the slot 34 of Fig. 1, has a curvature corresponding to the arc of movement of the end of the arm 45 about the pivot 18 so as to provide for movement of the arm 45 about the pivot 18 independently of the pin 43.

While we have shown a particular embodiment of our invention, it will be understood, of course, that we do not wish to be limited thereto, since many modifications may be made and we, therefore, contemplate by the appended claims to cover any such modifications as fall within the true spirit and scope of our invention.

What we claim as new and desire to secure by Letters Patent of the United States, is:

1. A circuit breaker comprising a switch mem-

ber mounted on a pivot for movement between open and closed circuit positions, an operating arm mounted on said pivot, means biasing said switch member with respect to said operating arm to said open circuit position, latch means normally securing said switch member against said biasing means in a predetermined relation with said operating arm, means for moving said operating arm to move said switch member between said open and closed circuit positions, current responsive means for actuating said latch means to release said switch member, and a pin and slot pivotal connection between said current responsive means and said latch means.

2. A circuit breaker comprising a switch member mounted on a fixed pivot movable between open and closed circuit positions, an operating arm mounted on said pivot, means biasing said switch member with respect to said operating arm to said open circuit position, latch means normally securing said switch member against said biasing means in a predetermined relation with said operating arm, means for moving said operating arm to move said switch member between said open and closed circuit positions, current responsive means for actuating said latch means to release said switch member, and a pin and slot pivotal connection between said current responsive means and said latch means, said slot being curved to provide for movement of said operating arm and said latch means together in a predetermined relation with respect to each other.

3. A circuit breaker comprising a switch member movable between open and closed circuit positions, an operating arm mounted on a fixed pivot, a spring biasing said switch member with respect to said operating arm to said open circuit position, latch means normally securing said switch member against said spring in a predetermined angular relation with said operating arm, means for moving said operating arm to move said switch member between said open and closed circuit positions, current responsive means for actuating said latch means to release said switch member, and a pivotal connection between said current responsive means and said latch means having an axis normally substantially coincident with the axis of said fixed pivot to provide for movement of said operating arm and said latch means together in a predetermined relation with respect to each other.

4. A circuit breaker comprising a movable contact, a switch member connected to operate said contact mounted on a fixed pivot, an operating arm mounted on said fixed pivot, a spring biasing said switch member with respect to said operating arm to operate said movable contact to its open circuit position, latch means normally securing said switch member against said spring in a predetermined angular relation with said operating arm, an operating handle, spring means connecting said handle with said operating arm for operation of said operating arm, a trip arm, current responsive means normally holding said trip arm, a pivotal connection between said trip arm and said latch means having an axis normally coincident with the axis of said fixed pivot to provide for movement of said operating arm and said latch means about said axis in a predetermined relation with respect to each other, and means biasing said trip arm to actuate said latch means to release said switch member when said trip arm is released by said current responsive means.

5. A circuit breaker comprising a movable contact, a link connected to operate said contact mounted on a fixed pivot, an operating arm mounted on said fixed pivot, a spring biasing said link with respect to said operating arm to operate said movable contact to its open circuit position, latch means normally securing said link against said spring in a predetermined angular relation with said operating arm, an operating handle, an overcenter spring connecting said handle with the free end of said operating arm for operating said arm with a snap action, a trip arm, current responsive means normally securing said trip arm in a predetermined position, a pivotal connection between said trip arm and said latch means having an axis normally coincident with the axis of said fixed pivot to provide for movement of said operating arm and said latch means in a predetermined relation with respect to each other, and means biasing said trip arm to actuate said latch means to release said link when said trip arm is released by said current responsive means.

6. A circuit breaker comprising a pivoted contact arm, a toggle having one link connected to said arm and a second link connected to a fixed

5 pivot, an operating arm mounted on said fixed pivot, a spring biasing said second link with respect to said operating arm to break said toggle and move said switch arm to its open circuit position, a latch member pivotally mounted on said second link and normally securing said second link against said spring in a predetermined angular relation with said operating arm, an operating handle having one end pivoted on said fixed pivot, an overcenter spring connecting said handle with the free end of said operating arm for operating said toggle with a snap action, a trip arm, a thermostat normally securing said trip arm in a predetermined position, a pivotal connection between said trip arm and said latch member having an axis normally coincident with the axis of said fixed pivot to provide for movement of said operating arm and said latch member as a unit in a predetermined relation with respect to each other, and means biasing said trip arm to actuate said latch arm to release said second link when said trip arm is released by said thermostat.
